UNITED STATES PATENT OFFICE.

MILLER REESE HUTCHISON, OF ORANGE, NEW JERSEY.

INSECTPROOF PORTAL CONSTRUCTION.

Application filed September 10, 1923. Serial No. 632,008.

To all whom it may concern:

Be it known that I, MILLER REESE HUTCHISON, a citizen of the United States, and a resident of Orange, in the county of Essex and State of New Jersey, have invented a new and Improved Insectproof Portal Construction, of which the following is a full, clear, and exact description.

This invention relates to the art of maintaining an unscreened opening in a building, or rather the atmospheric contents thereof, in a condition whereby winged insects are absolutely precluded from passing from the outside to the inside of the building by way of such opening. Obviously, the present invention has its greatest value in providing an insect-proof portal or doorway for use with buildings, such as dwellings, stores, stables and the like, having continuously open portals for admitting the free passage of human beings or other creatures, but in regard to which it is desirable to prevent any possible passage of flying insects.

One of the prime objects of the present invention is to provide certain improvements in the apparatus of my co-pending application Serial No. 658,069, filed August 18, 1923.

More specifically, among the objects contemplated by the present invention is that of providing apparatus for utilizing a discovery I have made as to the behavior of the columnar air-blast characteristic of the invention of said application (especially when a different form of rotary fan is employed from the one there shown) whereby increased insect-baffling efficiency is obtained, or, perhaps more accurately, whereby such efficiency is maintained uniform from top to bottom of the column; thereby, among other advantages, to permit persons to traverse the portal with less appreciation of special air velocity conditions, and to avoid the necessity for and the expense incident to the use of fumes, vapors or liquid particles, generally odorous, for admixture with the moving air continuously creating such column.

Another particular object of the present invention is to provide means for controlling such column whereby the downward velocity of the air streams forming the column may be predetermined more accurately

than heretofore, whereby in turn such velocity may be held closely to the ideal minimum required for efficient insect-bafflement.

Another particular object of the present invention is to provide a means for controlling such column whereby the cross-section of the same is maintained substantially circular from top to bottom thereof and opposite segments of the column are confined in laterally concave side walls of the portal, whereby in turn the insect-baffling efficiency of the portal is further increased.

A further particular object of the present invention is to provide means for controlling such column so as to preclude or reduce swirling air currents therein, even when the column is wholly or chiefly created by a rotary fan at the top or bottom of the portal.

With these and other particular objects in view, the invention consists in certain novel features of construction and combinations and arrangements of parts as will be more fully hereinafter described and pointed out in the claims:

In the accompanying drawing,

Fig. 1 is a vertical section taken through a portal constructed and equipped according to the invention, such section being taken in a plane parallel to the plane of the wall carrying the portal, such plane being located about midway of the depth of the vestibular portal characteristic of the application aforesaid;

Fig. 2 is a horizontal section, taken on line 2-2 of Fig. 1, and illustrating very clearly the incorporation in such a portal of one of the features of the present invention, to wit, side walls for the portal of arcuate cross-section;

Fig. 3 is a view similar to Fig. 1, but illustrating a modified form of blast-generating means, as well as a blast-controlling means which may be employed in association with the blast-creating means of Fig. 1; and

Fig. 4 is a horizontal section, taken on line 4-4 of Fig. 3.

The invention of the application aforesaid was based on a discovery of mine that a downwardly moving air barrier, and particularly such a barrier of a columnar character, as distinguished from the moving air sheets heretofore proposed, is exceedingly efficient for the purpose of precluding

winged insects, and especially flies, from passing from the outside to the inside of a building by way of a portal in which such air column is maintained; for the reason that the insects are unable to remain in flight when subjected to a down-draft, provided such draft is of sufficient width in the direction of depth of the portal or doorway to prevent an insect from completely traversing the blast in as short a time as the fraction of an instant required for the insect to pass through a thin sheet-like blast. Hence the characteristic columnar blast disclosed in that application; by which is meant a blast having a cross-section any dimension of which is considerable.

According to the present invention, such characteristic columnar blast is still employed; but is created and controlled according to further discoveries of mine, as will immediately below be explained fully in connection with a detailed description of the various structural features of the illustrative embodiments of the drawing.

From such drawing, it will be seen that each of the vestibular portals illustrated, in Figs. 1 and 2 and in Figs. 3 and 4, is in part established by a pair of side walls 5 and in part established by a floor grating 6 forming part of a floor 7. Any building or building sub-division between such a floor 7 and a roof or ceiling as indicated at 8 may be served by a portal constructed pursuant to the invention.

In the case of a portal constructed pursuant to the invention of the present application or of the co-pending application aforesaid, the columnar air blast is delivered from a point near the top of the portal from a rotary fan or blower 9 on a vertical axis; but in the case of the present invention such fan is preferably one having a plurality of vanes of the kind shown. The side walls 5, of both the portal constructions herein illustrated, are arcuate in cross-section as shown most clearly in Fig. 2. Now I have discovered that with certain types of fans, especially those having similar vane-elements to those of the fans 9, particularly when installed in a portal as just described and rotated so as to deliver a downward blast, such blast is of substantially constant velocity and true circular cross-section for an axial distance approximately equal to the effective diameter of the rotor of the fan.

Therefore, an important feature of the present invention, aside from all other features thereof, is a portal construction such that, as shown in the drawing, the effective diameter of the fan 9 is approximately that of the vertical distance between the point of establishment of the upper end of the air column to the lower end thereof at the grating 6 which forms the floor of the portal.

In the case of both Figs. 1 and 3, the upper

end of the column is located immediately below the fan 9.

In the case of Fig. 3, said upper end of the column is thus located, and also located at a point above a swirl-defeating or minimizing means including a fixed grill comprising a plurality of vertically arranged radially extending webs 10, rather thin and comparatively of considerable width transverse to their length. These webs converge toward meeting at the axis of the fan and at their inner ends are suitably secured to a tubular hub 11 and at their outer ends to a band forming part of an annular structure 12 within which fan 9 is located.

In both Figs. 1 and 3, a suitable spider 13 carries at its center a journaling mount 14 for the shaft of fan 9, such spider being suitably anchored at the outer ends of its legs to the portal construction. It will be noted that in the case of Fig. 3, the spider is anchored inside the annular structure 12.

In both Figs. 1 and 3, a receptacle filled with a suitable liquid, preferably oil, is provided as indicated at 15, for receiving the insects overborne and thrown down by the columnar air blast through floor grating 6.

Referring now particularly to Fig. 1, I have further discovered that the proper columnar air blast may be maintained, and one particularly efficacious for the purpose intended, if the portal construction of Fig. 1 as hereinabove described be further equipped with an auxiliary suction blower located below the floor grating 6, as indicated at 16. Fan or blower 16 is preferably the same general type of rotary fan as the fan 9 at the top of the portal. When a portal or doorway is thus equipped with a force blower at the top, and a suction blower at the bottom, especially when both the fans provided have effective diameters approximately that of the axial length of the column of air above the floor grating 6, and especially when the portal is vestibular and provided with arcuate side walls as at 5,—even with the parts 10, 11 and 12 of Fig. 3 omitted,—the air column may be kept at practically uniform velocity from top to bottom, continuously, and with comparative ease.

However, referring now particularly to Fig. 3, I have further discovered that practically the same advantageous results, and possibly even a more efficacious columnar down-draft may be provided, even with the fan 16 of Fig. 1 omitted, if the annular structure 12 is employed as shown, and particularly if such annular structure is employed in connection with the fixed grill including vanes 10 or an equivalent. Said annular structure, it will be noted, provides a vertical wind-tunnel, shaped in the present case like a Venturi tube; but it is essential, as I so far understand the present invention, and as

is borne out by actual tests, that the wind tunnel be so constructed about the fan that the fan is located therein considerably below the top of the tunnel, preferably about 5 midway between the top and bottom of the tunnel. Especially with such grill incorporated at the lower end of said annular structure, as above described, and with the grill located immediately below the fan 9, 10 to the end, as I have found, that all swirling action in the air column is almost if not completely throttled, the wind-confining and guiding means provided by the fixed parts of the annular structure 12 above and below 15 the fan 9, when said parts are shaped as shown in Fig. 3, is effective to insure a vertically downward flowing column of air which is of practically uniform velocity from top to bottom, and which, while easy 20 of passage by a person, is a certain bar to the passage of flying insects of even rather large size. It will be noted that the annular structure 12 is so designed as to have flared top and bottom end portions; with the upper 25 per mouth of the tunnel of greater diameter than the lower mouth thereof. So far as experimentation to date has shown, best results are obtained when the tunnel is so designed, as indicated on the drawing, that its 30 upper end portion 12^a is flared according to a radius of curvature 1.6 times the diameter of the fan, such flared portion merges gradually with a cylindrical portion 12^b opposite the fan, and said cylindrical portion diverges 35 into a bottom portion 12^c outwardly and downwardly flared at an angle of 3.5° to the portion 12^b.

It may be determined later on and after more extended experimentation that the construction of Fig. 1 in so far as two fans are employed, when equipped with the wind-tunnel and anti-swirling means of Fig. 3 or either of the latter, is the embodiment of the invention to be most preferred.

45 I claim:

1. An insect-proof portal construction comprising a doorway, air-blast producing means above said doorway and disposed to direct an air-blast substantially vertically downward in the form of a column of approximately circular cross-section, said means comprising a rotary fan on a substantially vertical axis, and a vertically disposed tubular structure substantially concentric 50 with the fan rotor and providing a substantially vertical wind-tunnel relative to the fan, said structure having its upper end located downward in the form of a column of approximately circular cross-section, said means comprising a rotary fan on a substantially vertical axis, and a vertically disposed tubular structure substantially concentric 55 with the fan rotor and providing a substantially vertical wind-tunnel relative to the fan, said structure having its upper end located at a point considerably above said rotor.

2. An insect-proof portal construction 60 comprising a doorway, air-blast producing means above said doorway and disposed to direct an air-blast substantially vertically downward in the form of a column of approximately circular cross-section, said 65 means comprising a rotary fan on a sub-

stantially vertical axis, and a vertically disposed tubular structure substantially concentric with the fan rotor and providing a substantially vertical wind-tunnel relative to the fan, said structure having its upper end located at a point above said rotor, the cross-sectional area of said tunnel decreasing gradually from the upper end of the tubular structure toward the rotor. 70

3. An insect-proof portal construction 75 comprising a doorway, air-blast producing means above said doorway and disposed to direct an air-blast substantially vertically downward in the form of a column of approximately circular cross-section, said 80 means comprising a rotary fan on a substantially vertical axis, and a vertically disposed tubular structure substantially concentric with the fan rotor and providing a substantially vertical wind-tunnel relative to the fan, said fan being located considerably below the top of the tunnel, and said structure also carrying means below said 85 rotor adapted to reduce swirling tendencies in the air column in the doorway. 90

4. An insect-proof portal construction comprising a doorway, air-blast producing means above said doorway and disposed to direct an air-blast substantially vertically downward in the form of a column of approximately circular cross-section, said 95 means comprising a rotary fan on a substantially vertical axis, and a vertically disposed tubular structure substantially concentric with the fan rotor and providing a substantially vertical wind-tunnel relative to the fan, said structure having its upper end located at a point above said rotor and said tunnel being shaped like a Venturi tube. 100

5. An insect-proof portal construction 105 comprising a doorway, air-blast producing means above said doorway and disposed to direct an air-blast substantially vertically downward in the form of a column of approximately circular cross-section, said 110 means comprising a rotary fan on a substantially vertical axis, the blades of the fan having a diameter substantially equal to the height of the doorway.

6. An insect-proof portal construction 115 comprising a doorway, air-blast producing means above said doorway and disposed to direct an air-blast substantially vertically downward in the form of a column of approximately circular cross-section, said 120 means comprising a rotary fan on a substantially vertical axis, said doorway being vestibular and of considerable depth, and being of a height substantially that of the diameter of the fan rotor. 125

7. An insect-proof portal construction comprising a doorway of predetermined height, and a blower arranged above said doorway and disposed to direct a blast of air substantially downward, said blower be- 130

ing of an effective diameter substantially that of the height of said doorway.

8. An insect-proof portal construction comprising a doorway, air blast producing means above said doorway and disposed to direct an air blast substantially vertically downward in the form of a column of ap-

proximately circular cross-section, and a wall on each side of said doorway of arcuate cross-section, closely enclosing said means whereby to maintain the columnar character of the air. 10

MILLER REESE HUTCHISON.
